UNITED STATES PATENT OFFICE.

CHARLES WILBER, OF MINNEAPOLIS, MINNESOTA.

ENGINE-SUPPORT.

1,127,708.

Specification of Letters Patent.

Patented Feb. 9, 1915.

Application filed October 1, 1914. Serial No. 864,474.

To all whom it may concern:

Be it known that I, CHARLES WILBER, a citizen of the United States, residing at Minneapolis, in the county of Hennepin and State of Minnesota, have invented certain new and useful Improvements in Engine-Supports; and I do declare the following to be a full, clear, and exact description of the invention, such as will enable others skilled in the art to which it appertains to make and use the same.

This invention relates to engine supports or holders especially designed for use in connection with the engines of Ford automobiles.

The object of the invention is to provide a simply constructed and efficient holder for engines while repairing or working upon them.

Another object is to provide a device of this character so constructed that it may be bolted on the motor block of the engine taking the same bolt holes that the water connections take, thus rendering the connection very simple and yet capable of reliably supporting the engine.

Another object is to provide a device of this character which may be adjusted into any desired position to enable any part of the engine to be reached.

With these and other objects in view, the invention consists of certain novel features of construction, and the combination and arrangement of parts as will be more fully described and claimed.

In the accompanying drawings: Figure 1 is a side elevation of the device showing its application in supporting a motor; Fig. 2 is a similar view with the motor swung to a different position; Fig. 3 is an end view with the parts standing as seen in Fig. 1; Fig. 4 is a vertical section taken on the line 4—4 of Fig. 3; Fig. 5 is a perspective view of parts of the device detached; and Fig. 6 is a detail horizontal section taken on the line 6—6 of Fig. 1.

In the embodiment illustrated, a tubular supporting standard 1 is shown having an apertured base plate 1' for connection with the floor, a bench or other suitable support. A head 2 has a shank 3 swiveled in the upper end of the standard 1, being preferably provided with an annular shoulder 4 for limiting its insertion in said standard and which is held in adjusted position by a set screw 5. The head 2 is here shown in the

form of a disk of heavy metal having a bolt 6 extending transversely therethrough and which passes through an arcuate slot 7 formed in an adjustable work supporting member 8 and which provides for the adjustment of this support 8 at any desired angle, said support being pivoted centrally to the head 2 by a suitable bolt or spindle 9.

An engine engaging bracket or arm 10 extends laterally at right angles from the outer face of the member 8 and is provided with an apertured lug 11, the apertures of which are designed to register with the bolt holes in the motor block of the engine which is to be supported and when suitable bolts are inserted in said apertures and the bolt holes in the motor block securely fastens the bracket to the engine. The free end of the bracket or arm 10 is curved to fit one of the cylinders of the engine to which it is to be applied and a similarly curved finger 12 projects laterally on the opposite side of the member 8 around the head 2 and is designed to engage another cylinder of the engine so that said engine is firmly engaged and held by said bracket and may thus be turned laterally in any desired direction by loosening the set screw 5 and turning the shank 3 of the head 2 in the socket formed by the tubular standard 1 and then again tightening said screw. To adjust the engine in a vertical plane, the bolt 6 is loosened and the member 8 with which the bracket is connected, is turned in any desired direction on the pivot 9 mounted in the head 2, the arcuate slot 7 moving around the bolt 6 and when the engine has been positioned as desired, this bolt 6 is tightened up and the engine will be held ready for work thereon.

From the above description, it will be obvious that this work holder is portable and may be moved and applied to any suitable support convenient to the operator and when an engine is held thereby, it may be placed in any position desired to render any certain part thereof accessible to the workmen.

I claim as my invention:

1. An engine support comprising a standard having a socket in its upper end, a flat vertically disposed head having a shank extending from its edge and revolvably mounted in said socket, means for holding said shank in adjusted position, an engine supporting bracket having a flat vertically disposed member pivoted centrally on said head

and having an arcuate slot therein concentric with its pivot, a bolt in said head extending through said slot, said bracket having an apertured lug with the apertures 5 therein positioned to register with bolt openings in the engine to which it is to be applied and curved fingers shaped to engage the cylinders of an engine.

2. An engine support comprising a tubular standard, a disk-like head having a radially extending shouldered shank revolvably mounted in said tubular standard, means 10 for locking said shank in adjusted position, a disk-like engine supporting member pivot-

ed centrally on said head and having an 15 arcuate slot therein arranged concentric with the periphery thereof, a bolt extending through said head and through said slot, and curved engine engaging elements disposed on opposite sides of said head and 20 shaped to fit the cylinders of an engine.

In testimony whereof I have hereunto set my hand in presence of two subscribing witnesses.

CHARLES WILBER.
